CIRCUIT BREAKER

George H. Perryman, Union City, and Paul Schwerin, Rutherford, N. J.

Application September 10, 1938, Serial No. 229,238

3 Claims. (CL. 200—144)

This invention relates to circuit breakers, and more particularly to those utilized in the timing mechanism of internal combustion engines.

The inefficiency of timing mechanisms utilized in connection with internal combustion engines, and particularly those used in automobiles is well known. Imperfect contact, arcing, pitting of the contacts, wear and other deficiencies often quickly arise and grow more aggravated as the motor receives use in time. The correction of these deficiencies requires time and effort on the part of the car owner or the service man; parts wear out and require replacement, and seldom does the average automotive engine operate with maximum efficiency due to the deficiencies mentioned and to improper adjustment of the parts, and particularly the contacts or so-called "points" of the circuit interrupter.

The object of the present invention is to provide a circuit breaker in which the contacts are enclosed in a chamber in which a high vacuum is initially produced and permanently maintained. Another object of the invention is to provide a chamber for enclosing the contacts, so constructed that a high vacuum may be readily produced within it, and also so constructed that one or both of the walls of the chamber will be flexible or resilient to thereby act as a means by which the contacts can be either opened or closed according to the design of operating mechanism employed in conjunction with the circuit breaker. Other objects are attained by the invention, as will be hereinafter pointed out.

In the accompanying drawing, wherein an embodiment of the invention is shown, Fig. 1 is a sectional view through the improved circuit breaker; Fig. 2 is a sectional view on the line 2—2 of Fig. 1, looking in the direction of the arrows; Fig. 3 is a side elevation of the device; Fig. 4 is a sectional view on the line 4—4 of Fig. 1, looking in the direction of the arrows; and Fig. 5 is a sectional view of a portion of a modified structure.

The circuit breaker contacts or "points" as they are commonly termed, are indicated at 1 and 2, the ends or faces 3 and 4 thereof being in abutment when the circuit is closed and spaced apart a slight distance when the circuit is open, as is clearly understood in this art. The contact 2, which may be the movable contact, is mounted in a dished plate 5 of concavo-convex formation, the same being preferably composed of metal and being flexible or resilient so that it normally holds the contacting face or end 4 of the contact member 2 firmly against the contacting face 3 of the

contact member 1. Contact member 2 is in two parts, one of which is welded on the outside of the plate 5 and the other on the inside so that the plate 5 is imperforate, and the contact member 2 becomes, for all intents and purposes, an integral part of the plate 5.

The dished plate 5 is formed with an integral marginal flange 7 in contact with a similar flange 8 formed at the edge of a dished plate 9 similar to that shown at 5 and in opposed position thereto. The abutting flanges 7 and 8 of the two plates 5 and 9 are welded together so that the two concavo-convex plates 5 and 9 co-operate in the formation of a chamber 10 within which the normally contacting ends 3 and 4 of the contact members 1 and 2 are disposed.

Contact member 1 is secured in the plate 9 by being fused thereto through the medium of a small body of glass 11 or other suitable insulation which will act not only to electrically insulate the contact member 1 from plate 9 but also to firmly attach the contact member 1 fixedly in the plate 9, and seal the plate around the contact member so that a high vacuum initially produced within the chamber 10 will be indefinitely maintained therein for the long life of the circuit breaker.

The casing or chamber, composed of the two opposed dished plates 5 and 9 as the walls thereof, fused or otherwise intimately secured together and securely sealed around the contact member 1 by means of the fused glass 11, is one in which a high vacuum can be readily secured and indefinitely maintained. By a "high vacuum" is meant a vacuum equivalent to that attained in electronic tubes and particularly those of present-day construction wherein a metal or glass envelope is employed to encase the tube elements. The securing of a vacuum equivalent to that attained in such tubes may be had within the chamber 10 by following the evacuating procedure employed in connection with electron tubes of the character mentioned, including the use of a chemical "clean-up" such as magnesium, barium compounds or the like. To facilitate the accomplishment of such evacuating procedure, the plate 9 is formed with an exhaust extension 12 which is sealed in the conventional manner after the exhausting of the chamber 10 takes place.

In the structure shown in Fig. 1 the contact members 1 and 2 are shown in normally closed position, the resiliency of the plate 5 tending to maintain them constantly closed. Contact 2 may be separated from contact member 1 by

any of the conventional breaker mechanisms and we have shown a lifter member 14, operated by the conventional cam mechanism, not shown, engaging an insulated nut 15 on the threaded end 16 of contact member 2, for breaking the contact of members 1 and 2 when required by engine operation. If desired, the device may be constructed for reverse operation. That is to say, the contact members may be normally held in circuit-breaking or open position and a means be employed for closing the circuit when desired by the operation of a pushing element acting against the end of contact member 2. In such case it might be found desirable to utilize a coil spring 17 as indicated in dotted lines in Fig. 1, within the casing 10 to normally hold the contacts in open position. These and various other modifications may be made without departing from the spirit of the invention. For example, while we have stated that the plate 5 may be flexible or resilient, it will be understood that both that plate and the co-operating plate 9 may be resilient.

In Fig. 5 is shown a modified structure where-in there is disposed between the flanges 7 and 8 a ring of suitable insulation 20 such as glass, the glass being fused to the flanges and acting as an insulation between the plates 5 and 9. With this arrangement, contact member 1 can be affixed directly to the plate 9 in the manner of contact 2, the glass indicated at 11 being in such case unnecessary.

By the enclosure of the contact members within a high vacuum, sparking, oxidation of the points, pitting and the other many deficiencies occurring with present-day structures is avoided and the life of the circuit-breaker greatly increased, not to mention the consistent uniform operating performance of the device for its entire life. The result is that consistently satisfactory engine performance is attained for long periods of time. In addition also, a closer spacing of the contacts may be used resulting in greater circuit-opening and closing speed.

What we claim is:

1. In a circuit breaker, a sealed metal casing in which a high vacuum is maintained, said casing comprising a pair of dished members, juxtaposed marginal flanges at the edges of the dished members in planes substantially parallel to the

planes of said dished members and secured together, one of said dished members being flexible and constituting a diaphragm, a contact carried centrally of said flexible member and having portions respectively disposed inwardly and outwardly of the casing, a second cooperating contact carried centrally of the other dished member and having an inner end of the contact cooperating with the contact carried by the flexible dished member and an outer end disposed outwardly of the casing and means for insulating the second contact from the flexible dished member. 5

2. In a circuit breaker, a sealed metal casing in which a high vacuum is maintained, said casing comprising a pair of dished members secured together at their marginal edges, one of said dished members being flexible and constituting a diaphragm, a contact carried centrally of said flexible member and having portions respectively disposed inwardly and outwardly of the casing, the other dished member having a central opening therein, a second contact cooperating with the aforesaid contact and extending through said opening and an insulation glass support for the second contact disposed in said opening and fused to the walls of said opening and to said second contact to insulate the second contact from the flexible dished wall. 15

3. In a circuit breaker, a sealed metal casing in which a high vacuum is maintained, said casing comprising a pair of dished members, juxtaposed marginal flanges at the edges of the dished members in planes substantially parallel to the planes of said dished members and secured together, one of said dished members being flexible and constituting a diaphragm, a contact carried centrally of said flexible dished member and having portions disposed inwardly and outwardly of the casing, a second contact centrally carried by the other dished member of the casing and having an inner end in the casing cooperating with the contact carried by the flexible dished wall and an outer end disposed outwardly of the casing and insulation means interposed between the marginal juxtaposed flanges of the dished members for insulating the second contact from the flexible dished member. 30 35 40 45
